(57) **CLAIM**

(**) Term: **14 Years**

I claim the ornamental design of a microarray slide cassette,
as shown and described.

DESCRIPTION

FIG. 1 is a perspective view of the microarray slide cassette
showing my new design;

FIG. 2 is a front view of the design, the rear view being a
mirror image thereof;

FIG. 3 is a right side view of the design;

FIG. 4 is a bottom view of the design, the top view being a
mirror image thereof;

FIG. 5 is a left side view of the design;

FIG. 6 is another perspective view of the design; and,

FIG. 7 is an enlarged view of the portion of FIG. 6 indicated
by a dashed circle.
